UNITED STATES PATENT OFFICE.

EUGENE W. VOGEL, OF OAK PARK, ILLINOIS, ASSIGNOR TO CHICAGO RAILWAY SIGNAL AND SUPPLY COMPANY, OF CARPENTERSVILLE, ILLINOIS, A CORPORATION OF ILLINOIS.

HIGHWAY-CROSSING BELL FOR RAILROAD SERVICE.

1,283,445.

Specification of Letters Patent. Patented Oct. 29, 1918.

Application filed May 27, 1914. Serial No. 841,319.

To all whom it may concern:

Be it known that I, EUGENE W. VOGEL, a citizen of the United States, residing at Oak Park, in the county of Cook, and State of 5 Illinois, have invented certain new and useful Improvements in Highway-Crossing Bells for Railroad Service, of which the following is a specification.

My invention relates to signaling devices 10 for railroad or like service, of a type commonly termed "crossing bells"; and the invention has for its object to provide a railroad crossing bell, operated by mechanism of the solenoid type, which will be simple in 15 construction, reliable in its operation, inexpensive to manufacture, and in which the operating mechanism is completely housed and protected against injury by rain, dust, and the like. A further object of the invention 20 is to provide certain novel improved arrangements whereby the ringing of the bell is accompanied by the production, automatically, of a visible signal in the form of an intermittent or flashing light. A further 25 object is to provide a solenoid operated signal bell which will produce a succession of loud, clear tones following each other at appreciable intervals. A further object is to provide certain adjustments as between the 30 contact springs for interrupting the operating circuit and the element employed for moving said contact springs whereby the mechanism is capable of being operated by currents of varying voltages.

35 The invention has for further objects such other new and improved constructions, arrangements and devices relating to highway signal bells as will be hereinafter described and claimed.

40 The invention is illustrated, in a preferred embodiment, in the accompanying drawings in which the figures numbered 1 and 2 are vertical sectional views taken at right angles one to the other; certain parts of the apparatus being shown diagrammatically.

Like characters of reference designate like parts in both figures of the drawings.

Referring to the drawings, 10 designates a casing open at the top and formed at the 50 bottom with a socket 11 for a supporting

post 12, or the like. The casing is formed with a preferably integral web 13 which provides a chamber 14 entirely inclosed except for a small opening or slot 15 in the top; the chamber 14 being intended to contain the 55 mechanism for operating the clapper of the bell. Access to the chamber is obtained through a door opening 16 formed in the outer casing 10 and normally closed by a door 17 hinged to the casing at 18 and preferably provided with a gasket 19 to make the door water and dust proof. The web 13 which divides off the chamber 14, is provided with an upstanding web or standard 20 on which the bell 21 is mounted, the bell 60 being preferably secured to the standard by a screw 22. The lower edge of the bell comes down close to and overlaps the casing 10 so that it covers the open top of the same. The casing is preferably provided with a 65 door 23 which may be secured in place by screws 24. The clapper 25 is formed upon or secured to a rocking member 26, the hub 27 of which is pivoted on a pin 28 between bosses 29 and 30 formed on the standard 20. 70 The rocking member 26 is formed with an arm 31 which is connected by a rod 32 passing through the opening 15 in the web 13 with the core 33 of the solenoid magnet 34 supported on a shelf 35. Within the chamber 14, arranged in the circuit 36 of the solenoid, is a pair of spring contact members 37, 38, which are normally together. The circuit 36 is adapted to be closed by any suitable mechanism, for example, by a circuit 80 closing device actuated by the movement of the trains. The core 33 of the solenoid carries a sleeve 39 which projects through an opening 40 in the bracket 35 and is internally threaded to receive a threaded rod 39^a which 85 is held in the desired adjusted position by a jam-nut 39^b and carries on its lower end a block 41 of fiber or other insulating material. When the magnet is energized the centering of its core brings the fiber block 41 against 90 the end of the spring contact member 38 separating this member from the contact member 37 and thereby breaking the circuit through the magnet. 95

Preferably the apparatus is provided with 100

a visible signal consisting of an electric lamp, shown conventionally in Fig. 1 of the drawings, designated 42. The lamp is on a normally open circuit 43 connected to the solenoid circuit 36 and containing a spring contact member 44 which stands below but out of contact with the contact member 38 when the core of the magnet is in its upper position. Contact member 38 is brought against the contact member 44, closing the lamp circuit, when the core 33 is drawn downwardly. It will be understood that the lamp 42 may be exposed in any suitable position with respect to the audible signaling apparatus. The spring contact members 37, 38, 44 are secured to studs formed on the adjustable plates 45, 46, 47, respectively, the studs being indicated by the common numeral 48. The plates are formed with arcuate slots 49 and are secured to a block 50, of slate or other non-conducting material, by means of set screws 51. By this arrangement the angular position of the contact members may be adjusted. The plates 45 and 47 are formed with lips 52 against which their respective contact members bear. Preferably a rubber or other resilient cushion 53 is affixed to the vertical portion of the web 13 in position to receive the clapper 25 on the rebound from the bell.

The operation of the device above described is as follows: When the circuit 36 is closed, for example, by the approaching train, the solenoid 34 is energized and its core 33 drawn downwardly. This rocks the member 26 toward the bell bringing the clapper 25 into contact therewith. The fiber block 41 on the lower end of the core is brought against the contact member 38 separating said member from the contact member 37 so as to break the solenoid circuit. It will be observed from Fig. 1 that in the normal position of contacts 37 and 38 the former stands away from its stop 52. As a result, during the first part of the downward movement or flexing of contact 38 there will be no separation of contacts 37 and 38, the former following along after contact 38 until contact 37 reaches its stop. This allows the solenoid to be fully energized and causes it to impart a powerful pull upon the bell clapper. In case the apparatus includes also the visible signal as shown contact member 38 toward the end of its movement meets the contact member 44 of the lamp circuit. This closes the lamp circuit and lights the lamp. With the solenoid deenergized the weight of the clapper assisted by the resiliency of spring contact 38 raises the core 33, breaking the lamp circuit and again closing the solenoid circuit. Soon after contact spring 38 begins to move or flex in the upward direction it comes against contact spring 37 and finishes its movement in con-

tact therewith. If the solenoid were energized instantaneously this would mean that the gravity of the clapper would be opposed by the magnetism of the solenoid. But as a matter of fact, the energization of the solenoid is gradual to a sufficient extent to permit the clapper to assume substantially its original or normal position before the magnet has pull enough to start another active or ringing stroke of the clapper. The advantage of having contacts 37 and 38 come together early in the back stroke of the apparatus is that in case there should be any tendency of the apparatus to stick or clog so that the parts fail to return to their normal position the apparatus is not left with an open circuit, which would make it inoperative. It is of the utmost importance that railway crossing signals should be as absolutely certain in their operation as possible. On this score the device of my invention is far more reliable than the signal bells of the type in which the circuit is closed by devices of one sort or another operated at the end of the back stroke of the clapper. In such signal bell apparatus, exemplified in patents to Slater & Barnes, No. 461,718, Bryant, No. 1,076,481, and Vogel, No. 1,091,548, the clapper and solenoid core are likely not to have force enough to operate the circuit closing device and these apparatuses have, therefore, proved unreliable in actual operation. With my apparatus it is possible to obtain a succession of loud clear sounds spaced at appreciable intervals like the sounds given out by a locomotive bell without any danger of having the apparatus put out of operation by failure of the circuit to close on a back stroke of the clapper.

While I have described my invention in a preferred embodiment, modifications might be made without departure from the principles of the invention. Therefore I do not wish to be understood as limiting the invention to the precise constructions and arrangements shown except so far as the same are made specifically limitations in certain of the claims herein.

I claim:

1. In a device of the character described, the combination with a casing open at the top and formed with a chamber extending above the upper edge of the casing and entirely inclosed except for an opening in the top and with a standard, of a bell secured to said standard so that it extends over the open top of said casing, a clapper pivoted to said standard, a solenoid arranged within said chamber, a connecting rod interposed between the core of the solenoid and said clapper, a pair of spring contacts normally together and in circuit with the solenoid, an element of non-conducting material car-

ried by said solenoid core adapted, when the solenoid is energized, to be brought against one of said contact members so as to separate it from the other member, and means 5 for adjusting the angular position of said contact members.

2. In a device of the character described, the combination with a bell and a clapper therefor, of a solenoid for operating the 10 clapper, a pair of spring contact members normally together, angularly adjustable and in circuit with the solenoid, means comprising an element of non-conducting material carried by the solenoid core which is ad- 15 justable with respect thereto for separating said contacts when the solenoid is energized, an electric lamp, a normally open circuit therefor, and an angularly adjustable spring contact member adapted to be engaged to 20 close the lamp circuit when said solenoid is energized.

3. In a device of the character described, the combination with a casing open at the 25 top and formed with a web which provides a chamber entirely inclosed except for an opening in the top and with a web forming a standard, of a bell secured to said stand- ard so that it extends over the open top of 30 said casing, a clapper pivoted to said stand- ard, a solenoid arranged within said cham- ber, a connecting rod interposed between the core of the solenoid and said clapper, a pair of spring contacts normally together 35 and in circuit with the solenoid, an element of non-conducting material carried by said solenoid core adapted, when the solenoid is energized, to be brought against one of said contact members so as to separate it from the other member, means for adjusting the 40 angular position of said contact members, a lamp on a normally open circuit connected with said solenoid circuit, and a contact member in said lamp circuit and arranged below and in the path of the contact mem- 45 ber which is moved by said solenoid core so as to be engaged by said contact member.

4. In a device of the character described, the combination with a bell and a clapper therefor, of a solenoid having a core con- 50 nected with the clapper to operate the same, means for operating the solenoid comprising an electric circuit for the solenoid and a source of electrical supply in said circuit, switch mechanism for opening and closing 55 said circuit, an element carried by said core for actuating the switch mechanism, and means whereby said switch mechanism and said element for actuating the same may be adjusted to maintain said circuit closed 60 throughout the entire movement of said core or through a portion only of said move- ment.

5. A railway signal bell apparatus comprising a bell, a depending pivoted clapper,

an electro-magnet, an armature for the mag- 65 net connected with the bell clapper in counter-balancing relation therewith, a pair of contacts in circuit with the magnet and means associated with the armature which operates when the armature is attracted by 70 energization of the magnet to cause said contacts to move together for a period and then to separate, said contacts adapted on the return stroke of the armature to come together and thereafter move in contact with 75 each other toward their initial position for the purpose described.

6. A railway signal bell apparatus comprising a bell, a depending pivoted clapper, 80 a solenoid having a core connected with the clapper in counter-balancing relation therewith, a pair of contacts in circuit with the solenoid, said core being adapted when the solenoid is energized to engage one of said contacts and move the same; one of said contacts comprising a spring, and said contacts being arranged so that during the first part 85 of the active stroke of the apparatus and the latter part of the return stroke thereof said contacts move with one bearing upon 90 the other.

7. A railway signal bell apparatus comprising a gong of the locomotive bell type, a clapper pivoted within the gong, 95 a solenoid having an armature connected with said clapper in counterbalancing relation thereto, and a pair of spring contacts each anchored at one end, one being flexed, in its normal position, with its free end bearing against the other, and the free end of the other extending into the path of said solenoid core so that said contact spring is bent and subsequently separated from the other contact spring when 100 the solenoid is energized.

8. A railway signal bell apparatus comprising a gong of the locomotive bell type, a clapper pivoted within the gong, a sole- 110 noid having an armature connected with said clapper in counterbalancing relation therewith, a pair of spring contacts each anchored at one end, one being flexed in its normal position, with its free end bearing against the other, and the free end of the other extending into the path of said sole- 115 noid core so that said contact spring is bent and subsequently separated from the other contact spring when the solenoid is ener- gized, and means for adjusting the angular position of said contacts for the purpose de- 120 scribed.

9. A railway signal bell apparatus comprising a gong of the locomotive bell type, a clapper pivoted within the gong, a solenoid having an armature connected with said 125 clapper in counterbalancing relation therewith, a pair of spring contacts each anchored at one end, one being flexed, in its normal

position, with its free end bearing against the other, and the free end of the other extending into the path of said solenoid core so that said contact spring is bent and subsequently separated from the other contact spring when the solenoid is energized, and an adjustable insulating device which pro-

vides the engagement between the solenoid core and the contact spring which is bent thereby.
